Inventor:

John H. Flynn Sr.

UNITED STATES PATENT OFFICE.

JOHN H. FLYNN, SR., OF CINCINNATI, OHIO.

STREET-CAR.

1,332,980.

Specification of Letters Patent. Patented Mar. 9, 1920.

Application filed July 19, 1918. Serial No. 245,631.

To all whom it may concern:

Be it known that I, JOHN H. FLYNN, Sr., a citizen of the United States, residing in Cincinnati, in the county of Hamilton and State of Ohio, have invented new and useful Improvements in Street-Cars, of which the following is a specification.

My invention relates to an improved street car in which the seating arrangement is designed to accommodate a greater number of persons seated than other car seating arrangements known to me, without taking from the standing room usually to be found in street cars.

15 This and additional objects are attained in the car described in the following specification and illustrated in the accompanying drawing which illustrates a sectional plan view of a car embodying my invention.

20 In my improved car construction I construct the seats so that they extend at an angle to the direction of the usual transversely alined seats, the inclination being to the rear preferably as shown in the drawing. 25 In dotted lines 2 I have shown the position of the usual seating arrangement in cars.

By means of my improved seating arrangement the number of persons which may

be seated on each seat, without crowding, is 30 three, as shown at 3, whereas in the usual directly transverse seats but two persons may be seated. This rearrangement of the seats may be made without taking up any of the space usually provided for seating room, 35 the space 4 left by the rearward inclination of the front seat being taken up by the space occupied by the rearward inclination of the rear seat, the width of the aisle 5 between the seats remaining the same, with little or no 40 difference in the distance 6 between adjacent seats.

Thus a maximum number of passengers may be seated without taking from the room which may be provided for standing a maximum 45 number of passengers.

Having described my invention what I claim is:—

A street car having seats extending from the sides toward an aisle formed in the center thereof and at an angle inclined to the rear.

In witness whereof I affix my signature in the presence of two witnesses.

JOHN H. FLYNN, Sr.
